(57) **CLAIM**

The ornamental design for covers for electric switches, as shown and described.

DESCRIPTION

The patent or application file contains at least one drawing executed in color. Copies of this patent or patent application publication with color drawing(s) will be provided by the Office upon request and payment of the necessary fee.

- 1.1. Top view of a cover for electric switches.
- 1.2. Bottom view of a cover for electric switches.
- 1.3. First side view of a cover for electric switches.
- 1.4. Second side view of a cover for electric switches.
- 1.5. Third side view of a cover for electric switches.
- 1.6. Fourth side view of a cover for electric switches.
- 1.7. Top perspective view of a cover for electric switches.
- 2.1. Top view of an embodiment of a cover for electric switches.
- 2.2. First side view of an embodiment of a cover for electric switches.
- 2.3. Second side view of an embodiment of a cover for electric switches.
- 2.4. Third side view of an embodiment of a cover for electric switches.
- 2.5. Fourth side view of an embodiment of a cover for electric switches.
- 2.6. Top perspective view of an embodiment of a cover for electric switches.
3. Top perspective view of another embodiment of a cover for electric switches.
4. Top perspective view of another embodiment of a cover for electric switches.
